UNITED STATES PATENT OFFICE

CHARLES ENOCH CONSTABLE, OF CINCINNATI, OHIO, ASSIGNOR TO THE NATIONAL
MARKING MACHINE COMPANY, OF CINCINNATI, OHIO, A CORPORATION OF OHIO

APPARATUS FOR CLASSIFYING LAUNDRY ARTICLES

Application filed June 28, 1928. Serial No. 288,979.

Laundry articles are usually received in a commercial laundry in individual family bundles which have to be broken and classified and assorted, and then conveyed to the proper washing mechanism, and at the same time the articles must be provided with suitable identification characters, whereby they may be collected and again formed into suitable bundles and delivered to the owners. A large amount of work is involved in the proper assorting and classifying of the laundry articles.

One of the objects of my invention is to provide an improved apparatus for use in breaking the individual family bundles of laundry and preparing them for the wash room, and separating and classifying the articles with a minimum amount of labor, and at the same time with a high degree of accuracy to avoid mistakes.

A further object is to provide a mechanism whereby the above method may be more easily and quickly carried out, and whereby the chances of mistakes and errors are greatly reduced, and further whereby the articles of the bundles may be passed progressively from one operator to another, the bundles being passed in a successive manner at regular intervals in such manner as to increase the speed of the work.

My invention consists in the construction, arrangement and combination of the various parts of the apparatus, whereby the objects contemplated are attained, as hereinafter more fully set forth, pointed out in my claims, and illustrated in the accompanying drawings, in which:

Figure 1 is a plan view of the mechanism used in my method.

Figure 2 is a side elevation of same.

Figure 3 is a vertical, longitudinal, sectional view taken on the line 3—3 of Figure 1.

Figure 4 is a transverse sectional view taken on the line 4—4 of Figure 1.

Figure 5 is an enlarged, detail view showing in side elevation one of the partition curtains and the frame for supporting the same.

Figure 6 is a detail sectional view taken on the line 6—6 of Figure 1.

Figure 7 is an enlarged top view of the

net holder showing the manner in which it is applied to the conveyor frame.

Figure 8 is a detail end elevation of the net holder, a portion of the supporting frame being shown in section.

Figure 9 is an enlarged, detail, sectional view taken on the line 9—9 of Figure 1, illustrating the automatic switch.

Figure 10 is a side elevation of said switch.

Figure 11 is a diagrammatical view of the electric circuit.

My improved apparatus comprises a frame 10 supported by legs 11. The ends of the frame 10 are provided with rollers 12 and 13 designed to support and carry a continuous belt 14. The upper run of said belt is designed to travel on a slatted platform 15. The frame 10 has upwardly extending side members 16 and 17, which extend substantially the entire length of the frame. The member 16 terminates inside of the end of the frame a slight distance, while the member 17 terminates a greater distance from the same end of the frame. A short side member 18 is provided so that a notch or opening 19 is formed.

The side members of the frame 10 consist of angle irons having upwardly extending flanges 20. Said upwardly extending flanges are designed to adjustably support a number of upright frame members 21. The upper ends of the frame members 21 are connected by a cross member 22. The lower ends of the members 21 have gusset plates 23, each of said plates being provided with slots 24 for receiving bolts 25 by means of which the said plates are adjustably secured to the flanges 20, for purposes hereinafter made clear.

The belt 14 is provided with a series of transversely arranged upright cleats 26, which are of a height substantially equal to the height of the side members 16 and 17, and of a length slightly less than the distance between said side members, as clearly illustrated in Figure 4.

The back side of each of the cleats 26 is provided with braces 27, the lower ends of which rest loosely on top of the belt 14.

Said braces prevent rearward movement of the top edge of the cleat 16 as the belt is advanced, the belt being designed to travel in an anti-clockwise direction, as illustrated in Figures 1, 2 and 3. The cleats 26 are equally spaced apart, substantially six or eight feet in the full size apparatus.

The cleats 26 of the upper run of the belt and the side members 16 and 17 form compartments 28 for receiving the laundry articles, each compartment being designed to receive and carry all of the articles of an individual family bundle.

A chute 29 is provided at the receiving end of the belt, having its lower edge terminating at a point immediately above the first one of the cleats 26, as illustrated in Figure 3. A suitable platform 30 is designed for receiving the individual family bundles.

The frame members 21 are spaced the same as the spacing of the cleats 26, and are designed to rest substantially above said cleats when the first one of the cleats is under the delivery edge of the chute 26, as illustrated in Figure 3.

Each of the members 22 is provided with a downwardly extending curtain 31, preferably formed of heavy canvas or similar material, the width of said curtains being substantially equal to the width of the cleats 26. The lower edges of the curtains have reinforcing bars 32 supported slightly above the upper edge of the cleats 26, so that the said cleats will pass freely beneath the members 32 without engaging the same. The lower edge of the canvas 32 is free to swing forwardly in case the laundry articles should extend above the upper edge of the cleats 26, and permit the articles to pass beneath the same without injuring the articles or the curtain. The curtains 31 provide partitions to prevent the articles of one compartment from becoming mixed with those in another compartment while the assorting is taking place.

Adjacent to the rear end of the side member 17, and outside of the frame 10 is a pair of bag or net holders 33, and spaced rearwardly from the net holders 33 is another net holder 34. The net holder 34 and the rear net holder 33 are spaced apart such a distance as to permit an operator to stand between them, said spacing forming what I shall term station D. The opposite side of the frame 10 is provided with a pair of net holders 35, spaced apart to receive an operator between them, said space forming station E. Operators are also located at stations A, B and C.

The roller 12 is provided with an extended shaft 36 having a belt wheel 37 driven by means of a belt 38 from an electric motor 39, by means of which the conveyor belt is operated.

Each of the net holders 33, 34 and 35 is formed of an angle iron frame 40 having spaced parallel members 41 projecting transversely under the side members of the main frame, and beneath the bottom 15, as clearly illustrated in Figures 7 and 8. The vertical flange of the angle 40 is provided with openings 42 for receiving the screw threaded ends of the rod 43, said rod being supported above and parallel with the angle 40, and having its ends bent inwardly and downwardly and thence rearwardly through the openings 42. Suitable nuts 44 are provided for locking the rod 43 in position.

The horizontal flanges of the members 41 are provided with slots 45 for receiving the ends of a rod 46, which is parallel with the rod 43, and has its ends bent downwardly and rearwardly and projecting through the slots 15, and thence forwardly and terminating in ends 47. The ends 47 are mounted in pipes 48 secured to the horizontal flanges of the angles 41 by suitable U-bolts 49. The forward end of each of the members 47 has a collar 50 and a spring 51, one end of said spring resting against said collar. The opposite end of the spring 51 rests against the rear end of the pipe 48, so that the rod 46 is yieldably supported in the forward ends of the slots 45.

By this arrangement it will be seen that openings 52 are provided between the members 40 and 41 and the rods 43 and 46. Said openings are designed to receive the upper ends of nets or bags 53, said upper ends being first lapped over the rod 43 and the opposite side then folded outwardly over the rod 46, said rod being moved to its outer limit of movement. The springs 51 will then draw the rod 46 inwardly and cause the bags 53 to be supported in the manner illustrated in Figure 8. This provides means whereby the bags may be easily and quickly placed in position, and when so placed will be firmly supported with the upper ends firmly held in an open position so that laundry articles may be easily and quickly placed therein.

For starting and stopping the belt 14, I have supported in the electric circuit of the motor 39 a switch 54, the opening and closing of which will cause the motor 39 to be operated and stopped, and in turn the belt 14 advanced and stopped.

It is desirable to stop the belt with the cleats 26 beneath the curtains 31. This I have accomplished by mounting on one end of each of the cleats 26 a trip bar 55 having its outer end bent upwardly at 56. Said members 56 are designed to engage the under surface of a pivoted switch arm 57, mounted on a shaft 58 rotatively and slidably mounted in a support 59. One end of the support 59 is bent inwardly at 60 and has its under surface provided with an insulating block 61, having a contact member 62 to coact with a

contact member 63 carried by the shorter end of the arm 57.

A spring 64 is mounted on the shaft 58 between the arm 57 and the support 59 to yieldably support the arm 57 at its inner position of movement and in alinement with the member 56, with the contact members 57 and 62 closed. Said contacts are included in the conductors 65 of the motor circuit, and the 10 motor will be rotated and the belt 14 advanced together with the cleats 26 until the member 56 engages the under surface of the lever 57, which will cause said lever to be rocked and the contacts 57 and 62 opened. 15 This will cause the motor 39 to stop and in turn the belt 14 with a cleat 26 immediately below the lower edge of the curtain 31. The contacts are held open by the member 56.

When it is desired to advance the belt, the 20 operator grasps the knob 66 on the outer end of the shaft 58 and pulls the said shaft outwardly, causing the member 57 to disengage the member 56 and the contacts 57 and 62 closed.

25 In this connection it should be noted that the spring 64 is both a torsional and extensible spring, which performs the double function of holding the member 57 inwardly and the electric contacts closed.

30 The switch 54 is located near the delivery end of the belt where it may be actuated by either of the operators in stations D and E. The switch, however, is illustrated as being mounted on the side member 18 and near the 35 operator in station D.

In operation with my apparatus an operator is placed in each of the stations A, B, C, D and E and the individual family bundles 67 are placed on the platform 30. The operator 40 at station A first weighs one of the individual family bundles 67, records the weight of the bundle and also the number of the bundle identification device, which is preferably a pin with a number stamped thereon. A pin tray 68 is placed on the belt 14, said tray carrying a number of pins having the same numbers as the identification number recorded. The bag is then broken and the contents emptied in the chute 29, and then delivered to the 50 first compartment. The laundry articles of said bundle are designated by the numeral 69.

The empty bag 67 is then placed on the belt 14 adjacent to the second cleat 26, as indicated at 70. The knob 66 is then grasped and pulled 55 outwardly, causing the motor to be started in the manner above described. As soon as the motor is started, the operator releases the knob 66 which permits it to automatically return to its normal position. The belt is then 60 advanced a distance equal to the spacing between two adjacent cleats 26. The articles 69 will then rest in the second compartment from the receiving end of the conveyor in front of the operator in station B.

65 A second bundle is at this time introduced

into the chute 29 as above described. At the same time the operator in station B separates the white articles from the colored ones, throwing the white articles in a pile 71 adjacent to the forward cleat 26, and the colored 70 articles in a pile 72 adjacent to the rear cleat, as indicated in Figure 1, and at the same time spreading out the articles for washing.

At this time the belt is again advanced one step in the manner above described, bringing 75 the piles 71 and 72 in front of station C. The operator at station C then classifies the pile of colored goods 72. In the present instance, these colored goods are separated into five 80 classes, as shown in Fig. 1. For instance, the two piles 73 may be one dark and the other light colors, the pile 74 may be fugitive colors, the pile 75 colored woolens and the pile 76 articles which must be washed by hand.

The conveyor is again advanced one step, carrying the piles 73 in front of the operator at station E and the piles 74, 75 and 76 in front of the operator at station D. The operator in station E then removes the bag 70 and places it in one of the holders 35, and another bag in the other holder, after which the articles in the piles 73 are placed in the bags in the holders 35. Said bags are then pinned with identification pins taken from the tray 68. The operator in station D at the same time places the colored articles in a net in the holder 34 and the fugitives and hand wash articles in nets in the holders 33, and pins the nets with identification pins from the tray 68, after which the nets are ready for 95 distribution to the proper washing machines.

By this arrangement it will be seen that the belt is advanced a step at a time and automatically stopped and manually started by the operator in station D. The operators in all 105 the stations perform the various operations simultaneously, and at the time the belt is in a stationary position.

By this arrangement team work is established among the operators and the operator in one station must perform her work in the same length of time as required for the operators in the other stations, thereby preventing delays and confusion, that might otherwise be caused by one operator not keeping up with 110 her work. By this method the work is rapidly and accurately performed.

It will readily be seen that the articles of a given bundle are placed in a compartment and retained in said compartment as it is advanced through all of its operations, the associated piles being placed in suitable nets or bags, all of the bags being pinned with pins from a single tray so that the bags may be collected after the washing is performed and the articles again placed in suitable bundles, on which is placed the original ticket or identifying number.

In this connection it should be borne in mind that each time a new bundle of washing 130

is placed in the chute 29, a new pin tray is also placed on the belt 14, the pins of which have a different identification number.

The side member 16 is shorter than the bet to provide a notch or opening through which the laundry articles may be delivered to the bags in the holders 35. The opening 19 permits material to be delivered to the bags in the holders 33 and 34.

10 The identification pins and trays may be of any one of a number of such devices now in common use, or other identification means may be substituted for the pins.

15 The frame members 21 are adjustably mounted to the members 20 to permit the curtains to be properly alined with the cleats.

I claim as my invention:

1. In a laundry classifying apparatus, the combination of a frame, a conveyor mounted 20 in the frame and designed to receive and support articles to be classified, transverse partition members fixed to and carried by the conveyor and extended upwardly from the upper portion of the conveyor, stationary 25 side walls at the side edges of the conveyor and extended above it, the said conveyor, the side walls and the partitions forming a series of classifying compartments designed to receive and support articles being classified 30 into groups upon the conveyor and to confine said articles within their respective compartments, one of the compartments thus formed being provided with openings in its said side walls through which articles upon 35 the conveyor may be scraped off at the side of the conveyor.

2. In a laundry classifying apparatus, the combination of a frame, a conveyor mounted 40 on said frame and designed to receive and support articles to be classified, transverse partition members supported on the frame above the conveyor to divide the conveyor into a series of classifying compartments, said partition members being capable of movement away from the conveyor to permit the conveyor to be advanced without disturbing 45 articles thereon.

3. In a laundry classifying apparatus, the combination of a frame, a conveyor mounted 50 on said frame and designed to receive and support articles to be classified by hand, transverse partition members supported on the frame above the conveyor to divide the conveyor into a series of classifying compartments, said partition members being pivoted at their upper ends so that their lower ends 55 may swing with the conveyor in the same direction as the conveyor is moving to thereby ride over any articles on the conveyor and 60 to prevent the articles from being disturbed in their positions on the conveyor.

4. In a laundry classifying apparatus, the combination of a frame, a conveyor mounted 65 on said frame and designed to receive and support articles to be classified, transverse

partition members supported on the frame above the conveyor to divide the conveyor into a series of classifying compartments, said partition members being capable of movement away from the conveyor to permit 70 the conveyor to be advanced without disturbing the articles thereon, partition members carried by the conveyor and spaced apart from each other to the same extent as are the partition members carried by the frame and 75 so arranged that the partition members on the frame and the partition members on the conveyor co-act with each other in confining articles upon the conveyor into separate compartments.

5. In a laundry classifying apparatus, the combination of a frame, a conveyor on the frame designed to receive and support articles to be classified, transverse partitions for 80 dividing the conveyor into a series of classifying compartments, means for advancing the conveyor and means for automatically stopping the conveyor each time that it has advanced a distance equal to the length of a 85 classifying compartment between the partitions.

6. A laundry classifying apparatus of the class described comprising a conveyor designed to receive and support articles to be classified, partition members carried by the conveyor extended transversely thereof 90 equally spaced apart and projected upwardly from the upper length of the conveyor, stationary side walls at the side edges of the conveyor and projected upwardly from it, partition members mounted on fixed supports and equally spaced apart the same distance as the partition members on the conveyor, said parts being so arranged that when the conveyor is stationary the partition members 95 on it and the partition members on the stationary supports may be in vertical alignment to co-act with each other in dividing the conveyor into separate compartments, means for manually starting the conveyor, 100 and means for automatically stopping the conveyor when said partition members are in substantially vertical alignment.

7. A laundry classifying apparatus including spaced upright partitions forming between them hand classifying compartments, a hand classifying laundry support movable in a plane adjacent said partitions and provided with upright cleats spaced apart as the partitions are spaced, means for moving the support relatively past the partitions, and stop means for arresting the movement of the support with the cleats in substantial alignment with the partitions.

Des Moines, Iowa, June 18, 1928.

CHARLES ENOCH CONSTABLE.
